Heribertus Marsh INVENTOR

UNITED STATES PATENT OFFICE.

RIVERIUS MARSH, OF NEW BRUNSWICK, NEW JERSEY.

DESIGN FOR A LAMP-CHIMNEY.

SPECIFICATION forming part of Design No. 30,080, dated January 31, 1899.

Application filed June 13, 1898. Serial No. 683,379. Term of patent 7 years.

To all whom it may concern:

Be it known that I, RIVERIUS MARSH, a citizen of the United States, residing at New Brunswick, in the county of Middlesex and State of New Jersey, have invented and produced a new and original Design for Lamp-Chimneys; and I do declare the following to be a full, clear, and exact description of the same, reference being had to the accompanying drawing, forming a part thereof.

My invention relates to a novel and artistic design for lamp-chimneys adapted for incandescent gas and other lights, and the leading feature consists in the cylindrical base and expanding side walls, which converge into a globular dome and cylindrical summit, supported by an angle formed in the open top of said dome.

In the said drawing letter A designates a cylindrical lamp-chimney of desirable proportions, pleasing to the eye. Letter B designates the lower walls of said chimney, which are vertical and expand in elevation and merge into a globular configuration, which terminates in a vertical angle that forms the base of a cylindrical summit, which is designated by letter A'.

What I claim is—

The design for a lamp-chimney, substantially as herein shown and described.

RIVERIUS MARSH.
